CLAIM

The ornamental design for a cabin for vehicles as shown and described.

DESCRIPTION

1. Cabin for vehicles

1.1 : Side perspective view

1.2 : First top perspective view

1.3 : Second top perspective view

Design 1 relates to cabins for vehicles as illustrated in the annexed drawings in which: FIG. 1.1 is a side perspective view of the cabins for vehicles of the present design; FIG. 1.2 is a first top perspective view thereof; and FIG. 1.3 is a second top perspective view thereof. Figure that shows the design most sufficiently: first top perspective view.
